Primary Examiner — Susan Moon Lee

(57) **CLAIM**

The ornamental design for a mobile computing terminal, as shown and described.

DESCRIPTION

FIG. 1 is a top perspective view of a mobile computing terminal;

FIG. 2 is a bottom perspective view thereof;

FIG. 3 is a top view thereof;

FIG. 4 is a bottom view thereof;

FIG. 5 is a first side view thereof;

FIG. 6 is a second side view thereof;

FIG. 7 is a front view thereof; and,

FIG. 8 is a rear view thereof.

Broken lines and unshaded portions contained within broken lines are not claimed.

1 Claim, 5 Drawing Sheets(56)
